UNITED STATES PATENT OFFICE.

EDWIN PRESCOTT, OF ARLINGTON, MASSACHUSETTS.

SHUTTER-OPERATING DEVICE.

1,329,927.

Specification of Letters Patent.

Patented Feb. 3, 1920.

Continuation of application Serial No. 875,857, filed December 7, 1914. This application filed March 18, 1916. Serial No. 85,192.

To all whom it may concern:

Be it known that I, EDWIN PRESCOTT, a citizen of the United States, residing at Arlington, in the county of Middlesex and 5 State of Massachusetts, have invented an Improvement in Shutter-Operating Devices, of which the following is a specification.

This invention relates to shutter-operating devices adapted to be actuated by means accessible at the interior of a building, and embodies many of the features of, and is intended as an improvement upon Letters Patents granted to me, #816,881, dated April 3, 1906, and #992,449, dated May 16, 15 1911, and is a continuation of my application, filed Dec. 7, 1914, Serial Number 875,857.

The present invention has for its object the provision of an oscillating swinging-member adapted to be connected with a turning shaft or member and arranged for connection with a bearing-plate on the shutter, with its axis of rotation in approximately parallel relation with the vertical plane of the shutter, and its center of motion in vertical alinement with the upper hinge, so that the device may serve as a hinge; also the provision of a housing on the bearing-plate arranged to receive the oscillating swinging-member, which is made adjustable, thereby to hold said member in different positions more or less removed from the shutter to accommodate reveals of various depth; also the provision of means for connecting the bearing-plate with the shutter, which admits of a transverse adjustment thereof with respect to the shutter, whereby the oscillating swinging-member may be held in proper relation with the hinge or hinges of the shutter and also admits of angular movement on and with respect to the shutter, so as to obtain the desired tension of the handle on the fastening-pin; also to construct an oscillating swinging-member comprising a 45 yoke and a short spindle extended at right angles from the crown of the yoke, said spindle being adapted to be supported by the housing on the bearing-plate and arranged with its longitudinal axis in parallel 50 relation with the vertical plane of the shutter; also the provision of a housing adapted to receive the spindle of the swinging-member and to hold said spindle against angular and longitudinal movements with respect thereto, except when in a predetermined po-

sition, in which position the housing may be withdrawn from the spindle for the purpose of detaching the shutter; also the provision of an adjustable bracket for supporting the means for connecting the rotating 60 swinging-member with the turning-shaft and for holding said swinging-member in different adjusted positions, more or less removed from the shutter, to accommodate reveals of different depths. The reveal is 65 ordinarily measured from the outer face of the casing to the outer line of the building wall. In different buildings and also in various parts of the country the reveals are of different depths.

Figure 1 is a front elevation of a portion of a shutter with an operating-device, embodying this invention connected thereto, the shutter being in closed position.

Fig. 2 is a plan view of the operating- 75 device connected with the shutter.

Fig. 3 is an enlarged side elevation of the bearing-plate and housing.

Fig. 4 is a vertical sectional view of the same.

Fig. 5 is an enlarged right-hand side elevation of the oscillating swinging-member, the turning-shaft, the bracket, and means supported by the bracket for connecting the turning-shaft with the oscillating swinging- 85 member.

Fig. 6 is a fragmentary view of the connecting-means.

Fig. 7 is a sectional detail view of the oscillating swinging-member and a portion 90 of the housing on the bearing-plate.

Fig. 8 is a side elevation of the parts shown in Fig. 5, the turning-shaft having been turned to swing the shutter half open, in which position it may be detached.

Fig. 9 is a fragmentary detail of the handle on the turning-member and its fastening-pin.

The turning-member or shaft 1, is adapted to receive a handle 1^a at one end, and has at 100 its other end an angularly formed end-portion 2. Said shaft has its bearings in a bracket 3, which is adapted to be attached to the outside of the casing by pins or nails 4, whereby it may be disposed at different distances from the casing according to the depth of the reveal. Said shaft is adapted for oscillation about a longitudinal axis, whereupon its end-portion 2 is correspondingly oscillated.

5 is a yoke with spindle 6 extended at right angles from the middle of its crown, which spindle has its bearings in the bracket 3, being disposed at about a 45° angle from the perpendicular. A block 7 is arranged between the arms of the yoke 5, and has journals at its ends which extend through holes in said arms and project beyond said arms. The angularly formed end-portion 2 of the turning-shaft is loosely connected or swiveled to said block 7 by a pin 8, here shown as arranged on the block.

The oscillating swinging-member consists of a yoke 10, having a short spindle 12, extended at right angles from the middle of its crown. The arms of said yoke 10 are spaced apart sufficiently to receive between them the yoke 5, and they are pivotally connected with said yoke, the projecting ends 20 of the journals at the ends of the block 7, which extend through arms of the yoke 5 entering sockets formed in the arms of the yoke 10, see Fig. 6, and serving as pivots. Through the medium of the yoke 5 and block 25 7, the oscillating swinging-member is connected with the turning-member or shaft 1, and is adapted to be swung in an approximately horizontal plane, and while so swung to be oscillated about its longitudinal axis. 30 15 represents a bearing-plate, see Figs. 1, 3, and 4, which has transverse slots 16 designed to receive bolts or screws 17, by which it is attached to the shutter, and is adjustable transversely with respect thereto, so that the 35 parts supported by it may be arranged substantially in vertical alinement with the axis of the hinge or hinges of the shutter; and also by means of said slots, said plate may be adjusted angularly so that the tension of 40 the turning-shaft and the engagement of its handle with its fastening pin 1^b may be varied. Said bearing-plate has a housing 20 for the short spindle 12 of the oscillating swinging-member, which housing is or may 45 be made adjustable in and out with respect to the bearing-plate. As here shown, see Figs. 3 and 4, the housing has two holes through it, arranged in parallel relation, which receive pins 21, projecting from the 50 bearing-plate, and said pins are made to tightly or frictionally engage the housing, so that the housing will be held in different positions it may be set with respect to the bearing-plate. In lieu of this means for adjustably connecting the housing with the bearing-plate, any other means may be employed, although in so far as certain features of my invention are concerned, the housing need not be made adjustable. The 55 bearing-plate is here shown attached to the inner stile of the shutter in a perpendicular position, or at least the housing 20 is so positioned, but it can be adjusted to other than a perpendicular position.

60 65 The housing 20 has a transverse circular

hole through it for the cylindrical spindle 12, which hole is arranged horizontally or thereabout and in substantially parallel relation with the plane of the shutter, and said spindle, while very short, is still made long enough to extend entirely through said hole, as represented in Fig. 1. In the form of housing here shown, its outer end-portion comprises two semicircular portions 25—25, arranged side by side, with a narrow space 75 between them, and the transverse hole extends for substantially half its diameter into said semicircular portions, as represented in Fig. 7. The spindle 12 has arranged on it intermediate its length a single tooth or projection 26, and in the hole in the housing a longitudinal slot 27 is formed, which extends partially through the housing, as for instance, it may extend through one of the semi-circular portions, see Fig. 8, so that when the spindle is arranged in the hole its tooth 26, will be arranged in the space between the portions 25. A transverse groove 28 is formed in the housing coincident with the space between said portions 25, of a depth corresponding with the length of said projection 26. This provides for the spindle 12 entering the housing when its tooth 26 is in alinement with the slot 27, and for being thereafter turned with respect to the housing, the tooth moving in the groove or in the space between the semicircular portions 25, according to its relative position to the housing. This slot and groove constitute a form of bayonet-slot which permits the housing to engage the spindle when in a predetermined position only, and to be held by the housing against longitudinal movement in all other positions. The positions of the slot in the housing and the tooth on the spindle, are arranged with respect to each other, so that the housing may be withdrawn from the spindle when the shutter is in "half-open" position, as in such position it may be easily attached and detached. The spindle 12 is held by the housing from moving angularly and longitudinally, so that during its full swinging movement it is forced to occupy the same plane, as contrasted to rising and falling as disclosed in my prior patents.

The parts having been assembled, and the shutter attached, the device is operated by turning the shaft 1, and as said shaft is turned, the oscillating swinging-member 120 10—12 is forced to swing about a substantially vertical axis to open and close the shutter, and also to oscillate about a substantially horizontal axis, and as it oscillates, its tooth 26 moves in the transverse 125 groove 28 of the housing and in the space between the semicircular portions 25, and arrives at a position in alinement with the slot 27, when the shutter is half-open, to admit of the shutter being removed when in 130

such position, but in all other positions, said oscillating swinging-member is held against longitudinal movement.

The device, as a whole, is very compact, 5 and is or may be adjustable throughout for reveals of different depths.

I claim:—

1. A shutter operating device, comprising an oscillating swinging member, adapted for 10 connection with a turning member, a bearing plate to be secured to the shutter, a housing to receive the oscillating swinging member and formed with spaced openings and pins carried by the bearing plate for adjustable friction fit within said openings, 15 whereby to permit adjustment of the housing toward and from the shutter.

2. A shutter operating device, comprising an oscillating swinging member adapted for connection with a turning member, a bearing plate, means connecting said plate to the shutter to permit transverse adjustment of the plate with respect to the shutter, pins carried by the bearing plate, and a housing to receive the oscillating swinging member and formed with spaced openings to adjustably receive said pins. 20 25

In testimony whereof, I have signed my name to this specification, in the presence of two subscribing witnesses.

EDWIN PRESCOTT.
